Primary Examiner — David G Muller*Assistant Examiner* — Christina Gabrielle Cosden(74) *Attorney, Agent, or Firm* — Hawaii Patent Services;
Nathaniel K. Fedde; Kenton N. Fedde(57) **CLAIM**

The ornamental design for a smart door lock, as shown and described.

DESCRIPTION

FIG. 1 is a front, right, top perspective view of the smart door lock, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the smart door lock and form no part of the claimed design.
